United States Patent Office.

HENRY O. HOOPER, OF DIAMOND SPRINGS, CALIFORNIA.

Letters Patent No. 92,531, dated July 13, 1869.

IMPROVEMENT IN DOOR-CLAMP.

The Schedule referred to in these Letters Patent and making part of the same.

To all whom it may concern:

Be it known that I, HENRY O. HOOPER, of Diamond Springs, in the county of El Dorado, and State of California, have invented a new and improved Power Door-Clamp; and I do hereby declare that the following is a full, clear, and exact description thereof, which will enable others skilled in the art to make and use the same, reference being had to the accompanying drawings, forming part of this specification.

This invention relates to a new and improved device for clamping doors and similar articles by means of horse, water, or other power than hand or human power; and

It consists in a novel construction and arrangement of parts, as hereinafter fully shown and described, whereby the device may be managed and operated with the greatest facility, and the work done in a perfect manner.

In the accompanying sheet of drawings—

Figure 1 is an end view of my invention in elevation.

Figure 2 is a longitudinal vertical section of the same, taken in the line $x x$, fig. 1.

Similar letters of reference indicate like parts.

A represents the base of the device, on which there are firmly secured bed-pieces B, which serve as guides for two clamps, C C.

These clamps are composed each of a horizontal bar, a, having two pendants, b b, attached, one near each end, said pendants being fitted between the bed-pieces B, and supported by rollers F, which work on the top of the bed-pieces.

The horizontal bars a a of the clamps have irons or brackets, c, attached to their outer sides, and between these brackets of the two bars a a the door is clamped.

The clamps C C are connected by right and left screw-rods D D, which pass through the pendants b b, as shown clearly in fig. 1.

On the centre of each screw-rod D, there is keyed

a worm-wheel, E, and into these worm-wheels screws c, on a shaft, F, gear, said shaft having its bearings, d, firmly secured to the base A, and the screws c gearing into the under sides of the wheels E.

On the centre of shaft F there is a drum, G, over which a straight and a cross-belt passes, in order that the shaft F may be turned in either direction, either belt being rendered operative and inoperative at the will of the attendant.

From the above description, it will be seen that placing the door on the bars a a, flatwise, and having the shaft F turn in the direction which will cause the right and left screw-rods D D to bring the clamps C C toward each other, the door will be firmly clamped, and all joints therein brought closely in contact, the door being relieved of pressure at any time by giving the reverse motion to shaft F.

The device is extremely simple and efficient, and will prove to be a great acquisition in clamping doors, greatly expediting the work, and doing the same in a more thorough and perfect manner than usual.

I am aware of the patent granted to Mr. McElroy, September 3, 1867, for an improved cotton-press, in which right and left-hand screws, operated by worm-gearing, are employed to move the platens; but this I do not claim, as it forms no part of my invention.

What I do claim, and desire to secure by Letters Patent, is—

The arrangement of the clamps C C, carrying the wheels F, and connected with the supporting bed-pieces B B, by means of the tongues and grooves, the right and left screw-rod D, the worm-wheels E, and the screws c c, formed on the central shafts F, all operating in the manner described, for the purpose specified.

HENRY O. HOOPER.
